(57) **CLAIM**

The ornamental design for a wing assembly for spoiler mountable to automobiles, as shown and described.

DESCRIPTION

FIG. 1 is a first view of the wing assembly for a spoiler mountable to automobiles.

FIG. 2 is a second view thereof.

FIG. 3 is a third view thereof.

FIG. 4 is a fourth view thereof.

FIG. 5 is a fifth view thereof.

FIG. 6 is a sixth view thereof.

FIG. 7 is a seventh view thereof.

FIG. 8 is an eighth view thereof, showing the mirror image of the wing assembly for a spoiler mountable to automobiles.

FIG. 9 is an ninth view thereof, showing the mirror image of the wing assembly for a spoiler mountable to automobiles.

FIG. 10 is an tenth view thereof, showing the mirror image of the wing assembly for a spoiler mountable to automobiles.

FIG. 11 is an eleventh view thereof, showing the mirror image of the wing assembly for a spoiler mountable to automobiles.

FIG. 12 is a twelfth view thereof, showing the mirror image of the wing assembly for a spoiler mountable to automobiles.

FIG. 13 is an thirteenth view thereof, showing the mirror image of the wing assembly for a spoiler mountable to automobiles.

FIG. 14 is an fourteenth view thereof, showing the mirror image of the wing assembly for a spoiler mountable to automobiles.

FIG. 15 is an fifteenth view thereof, showing the mirror image of the wing assembly for a spoiler mountable to automobiles; and,

FIG. 16 is an sixteenth view thereof, showing the mirror image of the wing assembly for a spoiler mountable to automobiles.

The shape of the wings on either end of the spoiler is the claimed design, shown in solid lines. The wings are mirror images of each other.

(Continued)

The broken lines showing parts of the spoiler form no part of the claimed design. The broken lines showing the swan neck-shaped central mounts form no part of the claimed design. The broken lines indicating the bottom portion of the wing assembly that is mounted on the automobile form no part of the claimed design.
